UNITED STATES PATENT OFFICE

EMIL FELDIN, OF EVERETT, WASHINGTON

LUMBER-LOADING ROLL

Application filed November 19, 1928. Serial No. 320,339.

This invention relates to improvements in means for handling lumber, beams, tubes, etc., and has particular reference to devices designed for loading lumber into or from cars. The device consists of a roll with means for mounting it on a car stake, or in a car door or like opening in the wall, and whereby the transfer of lumber or similar products into or from the car may be greatly facilitated.

The principal object of the present invention is to provide an efficient and relatively inexpensive mechanism by which the loading of materials of the above stated character may be greatly expedited, which may be easily and quickly attached or detached and which is easily adjustable to various positions required for meeting different conditions of operation.

More specifically, the invention resides in the provision of a lumber loading device consisting of a mounting in the nature of a clamp, that may be detachably fixed to a post, beam, stake or other supporting element and which is provided with a socket for receiving therein the mounting end of a laterally extending bracket which, at its outer end, supports a horizontally disposed roller over which the articles being loaded may be transferred; the clamp being adjustable to various positions on its support, the bracket being adjustable to different positions with respect to the clamp and the roller being pivotally adjustable to various horizontal positions relative to the bracket to thereby meet all conditions required for satisfactory use of a device of this character.

Other objects of the invention reside in the various details of construction and in the combination of parts, as is hereinafter described.

In accomplishing these objects, I have provided the improved details of construction, the preferred forms of which are illustrated in the accompanying drawings, wherein—

Figure 1 is a perspective view of a lumber loading device constructed and mounted in accordance with the present invention.

Figure 2 is a plan view of the same, illus-

trating the various adjustments of the roller and the supporting bracket.

Figure 3 is a view illustrating application of the device to a car doorway.

Referring more in detail to the drawings— 55

In its preferred form of construction, the present device comprises a mounting member in the form of a clamp that is adapted to be detachably secured to a supporting member, which may be a post, a door jamb, 60 a stake or beam, or other device suitable for the purpose. The clamp consists of a flat metal bar 1 provided with laterally directed portions 2 and 3 at its opposite ends adapted to be disposed at opposite sides of the support to which the device is to be applied. The end portion 2 is somewhat longer than the portion 3 and is bifurcated at its end and equipped with inwardly projecting toes 4 which aid in clamping the support and prevent slippage. The opposite end portion 3 is equipped with a suitable bearing, as at 3^a, through which a clamp screw 5 is threaded to extend toward the end 2, with a clamping pad 6 provided at its inner end and a handle, 70 or lever, 7 at its outer end whereby the screw may be rotated to adjust it to or from clamping position.

Formed adjacent one end of the clamp bar, 75 is a vertical socket 8 adapted to receive therein the mounting shank 9 of a horizontally directed arm, on the support 10. This support 10 consists of a flat bar which may be integral with the shank 9, and at its outer end, is formed with an upwardly directed portion 80 and a flattened base 11 upon which a yoke 12 is pivotally mounted by an attaching bolt 13. Supported within the yoke, is a horizontally disposed roller 15 this being equipped at its opposite ends with trunnions 90 16 pivotally contained in the upwardly directed end portions 12^a of the yoke. The bolt 13 which pivotally mounts the yoke on the support 10, extends downwardly through the base of the yoke and through the support 95 and, at its lower end, has a clamping lever 18 threaded thereon adapted to be tightened for the purpose of securing the yoke at any position to which it may be adjusted with respect to the support.

The socket 8 is of rectangular form and is adapted to receive the similarly shaped shank 9 of the roller supporting arm 10, and formed integral with the clamp so as to extend laterally from the bar 1 at one side of the socket, 5 is a supporting arm 20 upon which the arm 10 is adapted to rest when it is applied in the manner as shown in Figure 1. The construction provides that the arm 10 may be disposed at various positions with respect to the 10 clamp; that is, it may be placed in a position at which the arm 10 will extend perpendicular to the bar 1, and in another position parallel thereto, as shown in Fig. 2, and when in this latter position, the arm 10 will rest 15 upon a supporting lug 25 that is formed at the end of the bar 1 from which the clamp screw is supported.

In using the device, a clamp is first attached to the supporting member and then the shank 9 of the bracket, or supporting arm, 10 is inserted within the socket 8 of the clamp in such manner that the arm 10 will extend in the direction desired. If it is applied in such a manner that the arm 10 will extend at a right angle to the bar 1, then the lateral arm 20 supports the arm 10. If the arm 10 should be disposed in a position parallel with the bar 1, then it will be additionally supported by the lug 25 of the clamp. The roller 15 may be adjusted on the bracket to the desired angle in accordance with the direction in which it is desired to pass the material over it. By reference to Figure 2 of 25 the drawing, it is apparent how the position of the roller may be adjusted to various angular relations with respect to the support and it is also apparent how the supporting arm 10 may be disposed in different positions 30 with respect to the clamp. It will also be stated that the clamp may be inverted and reversed in its position and this provides that the supporting arm 10 may be reversed in its 35 positions with respect to those illustrated in 40 Figure 2.

Devices of this character may be made in various sizes and it is quite apparent that various details of construction could be altered without departing from the spirit of 45 the invention. For this reason, I do not wish to confine the scope of the claims only to the details of construction shown.

Having thus described my invention, what 50 I claim as new therein and desire to secure by Letters Patent, is:

1. A device of the character described comprising a clamp bar adapted to be detachably fixed to a support and having a socket therein, a bracket having a mounting shank applicable to the socket in various ways to support the bracket at different positions and a roller adjustably mounted by the bracket; said clamp having lateral supports extending therefrom for supporting engagement

with the bracket at points spaced from the shank.

2. A device of the character described comprising a clamp bar adapted to be adjustably and detachably fixed to a support and having a socket formed therein adjacent one end, a bracket having a vertical shank applicable to the socket in various ways to support the bracket at different positions, a yoke adjustably mounted by the bracket at its outer end and a roller mounted by the yoke; said clamp bar having an arm extended laterally therefrom adjacent the socket for supporting engagement with the bracket when the latter is disposed angularly with respect to the bar and having a lug projecting from the end of the bar opposite that at which the socket is formed for supporting the bracket when it is disposed parallel with the bar.

Signed at Seattle, Washington, this 8th day of November, 1928.

EMIL FELDIN.
